UNITED STATES PATENT OFFICE.

EDWIN M. CLARK AND CHARLEMAGNE CLARK, OF DETROIT, MICHIGAN.

SURFACE CATTLE-GUARD.

SPECIFICATION forming part of Letters Patent No. 408,695, dated August 13, 1889.

Application filed May 29, 1889. Serial No. 312,664. (No model.)

To all whom it may concern:

Be it known that we, EDWIN M. CLARK and CHARLEMAGNE CLARK, citizens of the United States, residing at Detroit, in the county of Wayne and State of Michigan, have invented certain new and useful Improvements in Surface Cattle-Guards, of which the following is a specification, reference being had therein to the accompanying drawings.

This invention relates to new and useful improvements in surface cattle-guards; and the invention consists in the peculiar construction of the sections composing the guard, whereby a more insecure footing is presented to the cattle than has been accomplished by previous constructions, thus giving a better protection from trespass by the cattle, at the same time cheapening the cost of manufacture and making it more readily removable when repairs to the track are required, all as more fully hereinafter described.

In the drawings which accompany this specification, Figure 1 is a plan view of the track with our improved surface-guard in position. Fig. 2 is an end elevation thereof. Fig. 3 is an enlarged plan view showing the construction of our guard, and Fig. 4 is an enlarged detail showing the manner of attaching the body of the guard to the side of the frame.

A are the rails. B are the ties composing the track, and C, C', and C'' are the three sections of which our guard is composed. These sections consist of a series of interlocking spiral coils D, the ends of which are secured 35 to the frame E by being turned around the frame and into the apertures F therein. Each of the sections is of the same construction, the central one C' being placed between the two rails and the outer ones C and C'' between each rail and the side fence, as is usual in guards of this kind.

We preferably make the frame E of rectangular shape, as shown in Figs. 1 and 3, section C securing the first coil around one of 45 the sides of the frame and interlocking the adjoining coils into it. It is evident, however, that the frame may consist simply of two bars, as shown in Fig. 1 at C' and C'', which are spiked or otherwise securely fastened to the ties, the other sides being secured

by means of spikes or staples H, driven on the edge of the coil.

We prefer to make the frame of rectangular shape, as it is evident that it can be more readily shipped than where the coils are loose 55 upon each other. The desired tension is also much more perfectly obtained by the use of the rectangular frame in manufacturing, the proper tension being necessary in both directions, so that a comparatively rigid mat is 60 formed.

The advantages of using the interlocking coils for the cattle-guard are, first, a great economy in manufacturing; second, all the parts presented upward by each turn of the 65 coil being circular it presents a much more irregular surface for footing for the animals, and should they step between the upturned coils the lower turn of the coil below presents another curved surface upon which the foot 70 would rest. In this way, with comparatively large spaces between the coils, the footing is destroyed for even the smaller animals.

In securing the ends of the interlocking coils into the frame we preferably do so by 75 forming two apertures F for each end of wire, as shown, bringing the end of the wire through one aperture, around the frame, and through the other aperture, thus giving it a firm hold upon the frame.

The sections are preferably laid directly 80 upon the ties, having a bearing upon all the ties embraced within their area. We preferably arrange the blocks or collars G under the frame at the points through which the spike 85 is to be driven.

The coils in practice are preferably constructed of four inches diameter and three and a half inches pitch, more or less.

What we claim as our invention is—

1. In combination with a railway road-bed, a surface cattle-guard secured thereto and constructed of sections of wire webbing having an upward presentation of loops or bends, substantially as described.

2. In combination with a railway road-bed, a surface cattle-guard secured thereto and constructed in sections, consisting of a wire webbing of interlocking spirals and the frame, substantially as described.

95

100

3. In a surface cattle-guard, the combination of the following elements: a rectangular frame, a web of interlocking wire coils connected at the sides and ends to the rectangular frame, and spools or blocks G, substantially as described.

In testimony whereof we affix our signatures,

in presence of two witnesses, this 6th day of May, 1889.

EDWIN M. CLARK.

CHARLEMAGNE CLARK.
